(57) **CLAIM**

The ornamental design for a license plate frame, as shown and described.

DESCRIPTION

FIG. 1 is a front perspective view of the license plate frame. FIG. 2 is a front view of the license plate frame of FIG. 1. FIG. 3 is a rear view of the license plate frame of FIG. 1. FIG. 4 is a top view of the license plate frame of FIG. 1. FIG. 5 is a bottom view of the license plate frame of FIG. 1.

FIG. 6 is a left-side view of the license plate frame of FIG. 1; and,

FIG. 7 is a right-side view of the license plate frame of FIG. 1.

The broken lines shown in the drawings form no part of the claimed design.

The broken line showing of the wire is show broken away to indicate indeterminate length.
